ASHTON G. STEVENSON, OF CHICAGO, ILLINOIS, ASSIGNOR TO CHICAGO LINO-TABLER COMPANY, OF CHICAGO, ILLINOIS, A CORPORATION OF ILLINOIS.

LUG-FORMING MATRIX.

1,012,741.

Specification of Letters Patent. Patented Dec. 26, 1911.

Application filed September 9, 1910. Serial No. 581,302.

To all whom it may concern:

Be it known that I, ASHTON G. STEVENSON, a citizen of the United States, and resident of Chicago, Cook county, Illinois, have invented certain new and useful improvements in Lug-Forming Matrices, of which the following is a full, true, clear, and exact description.

My invention relates to improvements in type casting machines of the linotype and similar kinds and has particular reference to matrices or molds with which to produce rule holding lugs upon linotype and similar type slugs or type bodies.

15 The object of the invention is to provide means with which a rule holding lug of peculiar shape may be formed upon a type body at the time that the type body itself is formed.

20 A further object is to provide means whereby rule holding lugs or projections can be conveniently and readily produced upon a linotype slug or a similarly cast line of type, in proper relative position to the other 25 characters thereon.

My invention consists in a mold or matrix of peculiar shape adapted for the formation of a rule holding lug of less than type height upon a type body, simultaneously with the 30 forming of the type body itself.

The invention further consists in a composed line of matrices certain thereof having type forms therein and others having recesses adapted to form lugs of less than type 35 height.

My invention will be more readily understood by reference to the accompanying drawings forming part of this specification and in which;

40 Figure 1 is a perspective view of a linotype matrix embodying my invention; Fig. 2 is a diagrammatic sectional view of a portion of a type slug casting machine showing the side elevation of a matrix in position 45 therein to form a rule engaging lug; Fig. 3 is an enlarged section similar to Fig. 2 but showing the matrix and the slug only; Fig. 4 is a view similar to Fig. 3 but showing the lugs formed lengthwise of the slug instead 50 of crosswise thereon; Fig. 5 is an enlarged 55 sectional view on the line 5—5 of Fig. 3 clearly showing the preferred shape of the lug forming recesses in the matrix; Fig. 6 is a sectional view on the line 6—6 of Fig. 2 similar to Fig. 5 but showing a line of mat-

rices and the type slug formed thereby; Fig. 7 is a perspective view of a type slug provided with rule engaging lugs formed by the use of matrices made in accordance with my invention; Fig. 8 is a perspective view 60 of a ruled type form illustrating the use of the rule engaging lugs; Fig. 9 is an enlarged view of a portion of a type slug illustrating a pair of rule holding lugs before being bent to engage the rule; and Fig. 10 is a view 65 similar to Fig. 9 but illustrating the lugs as bent into engagement with a triangular rule.

In said drawings 10 represents a matrix of the usual linotype form having recesses 11 of peculiar shape in one of its edges adapted 70 to form or produce lugs of peculiar shape upon and rising from the face of the type slug which is cast in the linotype machine.

In Fig. 2 the matrix 10 is shown in position between vise jaws 12 and 13, the jaw 13 75 being provided with a slot 14 in which the body of the slug is formed. The face of the jaw and the coacting face or edge of the matrix are coincident with the face of the slug formed by the coöperation of the jaw 80 and the matrix. The recesses 11 are indicated as being in position directly in front of the mouth of the slot 14 whereby the lugs produced by the recesses will be formed upon the face of the slug. In casting the slug, 85 the molten type metal is forced through the nozzle 15 filling the slot 14 and the recesses 11, in the usual manner.

As clearly illustrated in Fig. 5 which is an enlarged horizontal section of the slug and 90 matrix, the recesses 11 are V-shaped and are formed to produce thin lugs 16 upon the slug 17. These lugs 16 have their inner faces arranged parallel with each other and are formed with thin or knife edges and being thin are adapted to be easily formed, bent or compressed upon the ruling member with which they are designed to be used, to hold said member in position upon the slug. It is sometimes convenient to use these lugs 95 formed lengthwise on the slugs and in Fig. 4 I have illustrated a matrix having recesses formed in one of its edges at right angles to its length adapted to form these longitudinally arranged lugs.

My novel form of matrix is adapted to be associated with a plurality of matrices having recesses or molds in their edges adapted to form figures or other characters upon the slug. In Fig. 6 I have illus- 110

trated a composed line of matrices and the slug which would be formed thereby, in a linotype machine. Some of these matrices are provided with the lug forming recesses 5 11 and others with the figure or character forming recesses 18, the composed line of matrices being adapted to form the face of a complete linotype slug 17 having the rule holding lugs 16 thereon associated in proper 10 relation to printing characters 19 formed in the character recesses 18. The rule holding lugs 16 as clearly indicated in Fig. 6 are formed of less height than the characters 19, so that the edges of the lugs will 15 not form or print an impression upon the surface printed by the slug; consequently the rule forming recesses 11 are of less depth than the character forming recesses 18.

In Fig. 7 I have illustrated a typical 20 linotype slug provided with several pairs of rule holding lugs 16 spaced apart thereon in proper relative position to the various printing characters formed thereon. The lugs 16 on the slug in Fig. 7 and also 25 in Fig. 9 are shown in their cast or original condition, and in Fig. 10 I have illustrated a pair of the lugs as they appear when bent or pressed down upon the inclined side faces of the line printing rule 20.

30 In Fig. 8 I have illustrated a type form as composed of a plurality of linotype slugs 17 each of which is provided with a number of pairs of rule holding lugs 16 formed thereon in proper relative position, so that 35 when the slugs are assembled in column, the lugs on adjacent slugs form substantially continuous rule receiving slots, these slots being adapted to receive the rules 20 which rest upon the upper faces 21 of the slugs 40 and are supported thereby. After the rules 20 have been placed in the slots, the lugs 16 are formed or bent to engage the inclined side faces of the rules and retain them in position upon the type form.

45 While I have illustrated my invention as particularly adapted to the production of linotype slugs having rule holding lugs, it is readily seen that the lug forming recesses may be used in connection with other than 50 the linotype machines without departing from the spirit of the invention. I therefore do not limit my invention to a linotype matrix having these recesses, nor do I wish to be confined to a matrix for the production 55 upon a slug of a pair of associated rule holding lugs as it will be readily seen that alternate slugs may be formed with a single rule holding lug in such relation to single lugs upon associated slugs, that the lugs 60 will coact to retain a rule upon the type form.

Having thus fully described my invention, I claim as new and desire to secure by Letters Patent:

65 1. As an article of manufacture, a matrix

of the usual linotype character distinguished by two narrow, elongated recesses, arranged parallel with each other, in its mold face.

2. As an article of manufacture a matrix 70 of the usual linotype character distinguished by two narrow, elongated recesses arranged parallel with each other and situated one adjacent to each side face of the matrix.

3. As an article of manufacture a matrix 75 of the usual linotype character distinguished by two narrow, elongated V-shaped recesses, parallel with each other, and arranged one adjacent to each side of the matrix.

4. In a type slug casting machine, a composed line of matrices, adapted to form the upper portion of a type slug, certain matrices of said line having character forming recesses, and certain other matrices in said line, each of which has a pair of parallel 80 lug forming recesses of less depth than the character recesses.

5. In a type slug casting machine, a composed line of matrices, certain thereof having character forming recesses, and others 90 having narrow, elongated, tapered recesses of less depth than the character forming recesses.

6. In a type slug casting machine, a composed line of matrices, certain thereof having character forming recesses and others having narrow, elongated, V-shaped recesses of less depth than the character forming recesses.

7. In a type slug casting machine, a composed line of matrices, certain thereof having character forming recesses and others thereof each having two elongated, narrow recesses, arranged parallel with each other, and of less depth than the character recesses 10 and adapted to form upstanding lugs on the face of the slug, of less height than the printing character formed thereon.

8. In a slug casting machine, a composed line of matrices, certain thereof having character forming recesses, and others having narrow recesses of less depth than the character recesses and adapted to form parallel upstanding lugs on the face of the slug of less height than the printing characters 11 formed thereon, substantially as described.

9. As an article of manufacture, a matrix for use in type casting machines, characterized by having two parallel V-shaped slots for casting two spaced V-shaped lugs of less 1 than type height upon the product of the machine, substantially as described.

10. As an article of manufacture, a matrix of the usual linotype character distinguished by a narrow elongated recess, in 1 its mold face of less depth than the character recesses in similar matrices and adapted to form a non-printing projection upon linotype slugs, substantially as described.

11. As an article of manufacture, a ma- 1

1,012,741

trix of the usual linotype character distinguished by a narrow elongated recess V-shaped in cross section, in its mold face of less depth than the character recesses in 5 similar matrices and adapted to form a non-printing projection upon linotype slugs, substantially as described.

In testimony whereof, I have hereunto set my hand, this 29th day of August, 1910, in the presence of two subscribing witnesses.

ASHTON G. STEVENSON.
